attorney.

UNITED STATES PATENT OFFICE.

EDWIN C. DURAND, OF GREENWICH, OHIO.

BELT-SHIFTER.

SPECIFICATION forming part of Letters Patent No. 255,607, dated March 28, 1882.

Application filed February 14, 1882. (No model.)

To all whom it may concern:

Be it known that I, EDWIN C. DURAND, a citizen of the United States, residing at Greenwich, in the county of Huron and State of Ohio, have invented certain new and useful Improvements in Belt-Shifters, of which the following is a specification, reference being had therein to the accompanying drawings.

My invention relates to belt-shifters; and it consists in the construction and arrangement of its several parts, as will be hereinafter fully set forth, and pointed out in the claims.

In the drawings, Figure 1 is a side elevation of the shifter applied, and Fig. 2 is a vertical longitudinal section, and Fig. 3 is a top plan view.

A is the shifter. It consists of the side pieces, $a a$, formed as shown, and having cut in their straight edges the semicircular recesses $a' a'$, through which passes the pulley-shaft. They are secured together by the strips $a^2 a^2$, as shown. Journalled between the outer portions of the strips and projecting above their edges are rollers a^3 .

B and C are working-pulleys on the shafts $b c$, and are connected by the belt D, as shown.

E is one of the ceiling-joists. The semicircular recesses a' are placed over the shaft b

and the pulley made secure in position by the braces $e e$, attached to it and to the joist E. 30 The rollers $a^3 a^3$ will be on a level with the periphery of the pulley B.

F is the shifting-bar, and by it the belt D is thrown from the pulley B onto the shifter.

In operation, when it is desired to shift the pulley F, as the edges of the belt slip over onto the shifter its rollers a^3 will revolve on the belt and will prevent all "burning" or breaking of the leather. The braces $e e$ will prevent the belt from slipping off the shifter. 40

What I claim is—

1. The shifter A, consisting of the side pieces, $a a$, formed as shown, secured together by the strips $a^2 a^2$, and having journalled between them the pulleys a^3 , and adapted to be 45 secured to the joist E by the braces $e e$, substantially as shown and described.

2. The shifter A and its pulleys a^3 , in combination with the pulley B and shifting-bar F, all arranged to operate as set forth. 50

In testimony whereof I hereby affix my signature in presence of two witnesses.

EDWIN C. DURAND.
